UNITED STATES PATENT OFFICE

WILLIAM J. HALE AND EDGAR C. BRITTON, OF MIDLAND, MICHIGAN, ASSIGNORS TO THE DOW CHEMICAL COMPANY, OF MIDLAND, MICHIGAN, A CORPORATION OF MICHIGAN

MANUFACTURE OF PHENOLS

No Drawing.

Application filed July 3, 1929. Serial No. 375,873.

The present invention relates to the manufacture of phenols by means of the hydrolysis of the corresponding halogen substituted aromatic hydrocarbons, and more particularly to hydrolysis of such halogenated aromatic hydrocarbons through the agency of a salt of a strong base and a weak acid in aqueous solution.

The present application is a continuation in part of our copending application filed June 26, 1923, Serial No. 647,898.

The object of our invention is to provide a process of the aforesaid nature whereby free phenols are produced directly as distinguished from existing commercial processes wherein the alkaline salts of phenols, or phenates, are the immediate product, such phenates requiring to be treated further with an acid in order to liberate the phenols as such. Another object is to secure greater economy of raw materials entering into the process and consequently a lower cost of manufacture. Other objects and advantages will appear as hereinafter described.

To the accomplishment of the foregoing and related ends, the invention, then, consists of the steps hereinafter fully described and particularly pointed out in the claims, the following description setting forth but a few of the various ways in which the principle of the invention may be used.

It is well known that chlorbenzene can be hydrolyzed by dilute (10 to 20 per cent) aqueous solutions of caustic alkali by heating under pressure at temperatures up to 300° C. The basis of this method is set forth in detail by Meyer and Bergius (Berichte 47; 3155-3160, 1914). Taking as an example the production of phenol from chlorbenzene, the course of the reaction is given by the two equations;

Simultaneously a secondary reaction takes place according to the equation;

The diphenyl oxide so produced is then hydrated slowly to phenate at the reaction temperature of about 300° C. if a sufficiently large excess of caustic alkali solution is present;

The product obtained by this method is sodium phenate which must be treated with an acid to liberate free phenol, such method thus involving an extra step as well as the added expense of the acid. To secure a high yield of phenate, an excess of at least 2 moles NaOH is required over and above the 2 moles thereof theoretically called for according to equations (1) and (2). Such excess, of course, is lost when the reaction mass is acidulated and also necessitates the use of a correspondingly greater quality of acid for neutralization. Consequently, for each mole of phenol produced, approximately 4 moles of caustic soda and 3 moles of hydrochloric or other equivalent acid are consumed.

Following the method outlined above, Meyer and Bergius obtained a 96 per cent yield of phenol as phenate when they used 4 moles of NaOH, to one mole of chlorbenzene but with a smaller proportional amount of caustic soda the yield was appreciably diminished and diphenyl oxide was formed in correspondingly larger amount. While with caustic alkali a smooth substitution of Cl by OH was effected with a high yield, they found that other bases, e. g., lime, soda, borax, were almost without effect. For example, a yield of but 15 per cent of phenol was obtained when chlorbenzene was heated under pressure at 300° C. for 8 hours with sodium carbonate solution, and a like meager yield was obtained with borax solution in 9 hours at 297° C.

To summarize, the present processes for the production of phenols by the hydrolysis of halogenated aromatic hydrocarbons with aqueous caustic alkalis do not yield a phenol directly, but a phenate; a large excess of alkali is necessary to convert the diphenyl oxide formed as an intermediate product back to phenate, and an amount of acid equivalent to all of the alkali used is required for

decomposing the phenate and neutralizing the excess of alkali. Processes employing weaker alkalis have returned but a small yield of phenol experimentally, and heretofore have not been capable of successful commercial application.

In contradistinction to the published results of Meyer & Bergius (loc. cit.), we have now discovered that it is possible under appropriate conditions to obtain directly a high yield of free phenol, as distinguished from phenate, by replacing caustic alkali as hydrolytic agent with certain basic salts, which may be generally described as salts of a strong base and a weak acid, examples of which are the borates, carbonates, silicates and phosphates of the alkali metals.

Such basic salts in aqueous solution are slightly hydrolyzed by the action of water, a condition of equilibrium being set up, as illustrated in the following equations;

The equilibrium concentration of alkali hydroxide is normally very low but nevertheless it is sufficient to effect the exchange of hydroxyl for halogen in halogen substituted aromatic hydrocarbons when the latter are heated under pressure with an aqueous solution of one of the above basic salts at temperatures, in the case of chlorinated derivatives, for example, between 300° and 400° C.

During the progress of the reaction a very large excess of halogenated hydrocarbon, as compared with alkali hydroxide formed by hydrolysis, is always present in the mixture. Such hydroxide, therefore, is completely consumed in the production of the phenol, and no surplus thereof becomes available for neutralizing the phenol so produced to form phenate. The supply of alkali hydroxide is constantly replenished at about the same rate as it is consumed by further hydrolysis of basic salt.

The reactions between a halogenated aromatic hydrocarbon, e. g., chlorbenzene, and basic salts of the character herein described are expressed in the following equations;

In the course of the reaction the basic salt is converted into the corresponding acid salt in equimolecular proportion to the phenol formed. In Equation (8) the unstable sodium acid borate breaks down further into a more stable metaborate and metaboric acid. The reaction mixture on standing forms two distinct layers readily separable by mechanical means, one containing most of the phenol and the other an aqueous solution of the inorganic salts together with a little phenol.

The phenol layer may be purified in the usual way, as by distillation; the aqueous salt solution may be distilled with steam to separate the small amount of phenol dissolved therein and then regenerated simply by adding caustic alkali to convert the acid salt back to the basic salt, viz;

The alkali chloride concentration of the aqueous solution will naturally build up with continued operation until the solution becomes saturated therewith, after which further amounts of chloride produced separate in solid crystal form and are filtered off.

It will be noticed that the materials actually consumed in the process are chlorbenzene and caustic alkali. The basic salt is transformed to acid salt from which the former is regenerated by adding alkali. Such regenerated basic salt is then reused, so that the total amount of basic salt in circulation under continuous operation remains practically constant. Only one molecular equivalent of caustic alkali for each equivalent of phenol produced is required for regenerating the basic salt solution, whereas in other processes from two to four equivalents of alkali to one of phenol are consumed. Further, in our improved process no acid is required for neutralization. Thus important economies in the consumption of raw materials are effected.

The effective reacting temperatures depend in the first place upon the particular halogen substituent of the aromatic hydrocarbon, brom-substituted derivatives, of course, being more readily hydrolyzed than the corresponding chlor-derivatives. With the former temperatures as low as 250° C. may be sufficient, whereas with the latter commercial yields are obtained, as previously stated, at temperatures between 300° and 400° C. In practice we have found it advantageous to employ temperatures materially above 300° C., e. g. from 320° to 390° C., but above about 410° C., decomposition becomes appreciable.

Example 1

A mixture consisting of 1 mole chlorbenzene and 1.2 mole borax in approximately 10 per cent aqueous solution is placed in an autoclave and heated under pressure for 40 minutes at an average temperature of 370° C. The reaction product, after cooling and discharging from the autoclave, is allowed to separate into two layers, one containing free phenol and the other being an aqueous salt solution containing a little phenol dissolved therein. The phenol layer is distilled in the usual way for the separation of diphenyl oxide and unreacted chlorbenzene and the preparation of a purified phenol product. The aqueous layer is boiled to steam off its content of phenol, which is separately recovered.

ered, and then is treated with caustic soda in amount sufficient to regenerate the basic salt, whereupon the solution may be employed for a succeeding reaction. Yield of phenol is approximately 56 per cent, and of diphenyl oxide 13 per cent, based upon the chlorbenzene used. The excess of unreacted chlorbenzene is recovered and may be returned to a later reaction.

10 *Example 2*

A mixture containing 1 mole chlorbenzene and 1.2 mole of an approximately 14 per cent solution of sodium carbonate is heated under pressure at about 370° C. for 1 1/4 hours. The reaction product is worked up in similar manner as described in Example 1. Yield of phenol is approximately 60 per cent, and of diphenyl oxide 17 per cent.

15 20 The above described improved process is applicable generally to the production of phenols and substituted derivatives thereof by the hydrolysis of the corresponding mono- or poly-halogen substituted aromatic hydrocarbons as well as derivatives of such halogenated hydrocarbons containing other non-hydrolyzable substituent groups. For example, the mono-halogenated toluenes may be converted to the corresponding cresols, di- 25 halogenated benzenes to the corresponding dihydroxy phenols, halogenated naphthalenes to the corresponding naphthols, halogenated diphenyls to hydroxy-diphenyls, etc.

30 35 Other modes of applying the principle of our invention may be employed instead of the one explained, change being made as regards the process herein disclosed, provided the step or steps stated by any of the following claims, or the equivalent of such stated 40 step or steps be employed.

We therefore particularly point out and distinctly claim as our invention:—

1. The process of making a free phenol directly without acidification of the reaction product which comprises heating a halogenated aromatic hydrocarbon with an aqueous solution of a basic salt included in the group of the borates, carbonates, phosphates and silicates of the alkali metals under pressure at a temperature between 320° and 400° C.

2. The process of making a free phenol directly without acidification of the reaction product which comprises heating a halogenated aromatic hydrocarbon with an aqueous solution of a basic salt included in the group of the borates, carbonates, phosphates and silicates of the alkali metals under pressure at a temperature between 320° and 400° C., separating the phenol formed from the residual aqueous solution, regenerating the basic salt in the latter by adding caustic alkali and returning such solution to the initial reaction.

3. The process of making a free phenol directly without acidification of the reaction

product which comprises heating a chlorinated aromatic hydrocarbon with an aqueous solution of a basic salt included in the group of the borates, carbonates, phosphates and silicates of the alkali metals under pressure at a temperature between 320° and 400° C.

4. The process of making a free phenol directly without acidification of the reaction product which comprises heating a chlorinated aromatic hydrocarbon with an aqueous solution of a basic salt included in the group of the borates, carbonates, phosphates and silicates of the alkali metals under pressure at a temperature between 320° and 400° C., separating the phenol formed from the residual aqueous solution, regenerating the basic salt in the latter by adding caustic alkali and returning such solution to the initial reaction.

5. The process of making free phenol directly without acidification of the reaction product which comprises reacting chlorbenzene and an aqueous solution of a basic salt included in the group of the borates, carbonates, phosphates and silicates of the alkali metals under pressure at a temperature between 320° and 400° C. and a corresponding pressure.

6. The process of making free phenol directly without acidification of the reaction product which comprises reacting chlorbenzene and an aqueous solution of a basic salt included in the group of the borates, carbonates, phosphates and silicates of the alkali metals under pressure at a temperature between 320° and 400° C. and a corresponding pressure, separating phenol from the residual aqueous solution, regenerating the basic salt in the latter by adding caustic alkali and returning such solution to the initial reaction.

7. The process of making free phenol directly without acidification of the reaction product which comprises reacting chlorbenzene and an aqueous sodium carbonate solution at a temperature between 320° and 400° C. and a corresponding pressure.

8. The process of making free phenol directly without acidification of the reaction product which comprises reacting chlorbenzene and an aqueous sodium carbonate solution at a temperature between 320° and 400° C. and a corresponding pressure, separating phenol from the residual aqueous solution, regenerating the basic salt in the latter by adding caustic soda and returning such solution to the initial reaction.

9. The process of making a phenol which comprises reacting a halogenated aromatic hydrocarbon with an aqueous solution of a basic salt from the group consisting of the borates, carbonates, phosphates and silicates of the alkali-metals by heating under pressure at a temperature between 320° and 400° C., whereby the free phenol instead of a phenate is formed in the reaction mixture, and separating such phenol by mechanical

means without acidifying the reaction product.

10. The process of making a phenol which comprises reacting a chlorinated aromatic hydrocarbon with an aqueous solution of a basic salt from the group consisting of the borates, carbonates, phosphates and silicates of the alkali-metals by heating under pressure at a temperature between 320° and 400° C., whereby the free phenol instead of a phenate is formed in the reaction mixture, and separating such phenol by mechanical means without acidifying the reaction product.
11. The process of making phenol which comprises reacting chlorobenzene with an aqueous solution of a basic salt included within the group consisting of the borates, carbonates, phosphates and silicates of the alkali-metals by heating under pressure at a temperature between 320° and 400° C., whereby free phenol instead of an alkali-metal phenate is formed in the reaction mixture, and separating said phenol by mechanical means without acidifying the reaction product.
12. The process of making phenol which comprises reacting chlorobenzene with an aqueous sodium carbonate solution by heating under pressure at a temperature between 320° and 400° C., whereby free phenol instead of the sodium phenate is formed in the reaction mixture, and separating said phenol by mechanical means without acidifying the reaction product.

Signed by us, this 28 day of June, 1929.
